* cited by examiner

Primary Examiner — Robert M. Spear(74) *Attorney, Agent, or Firm* — Sterne, Kessler, Goldstein & Fox P.L.L.C.(57) **CLAIM**

The ornamental design for a tire, as shown and described.

DESCRIPTION

FIG. 1 is a front perspective view of a tire showing the claimed design;

FIG. 2 is a front view thereof;

FIG. 3 is a rear view thereof;

FIG. 4 is a top plan view thereof;

FIG. 5 is a bottom plan view thereof;

FIG. 6 is a right side view thereof;

FIG. 7 is a left side view thereof;

FIG. 8 is an enlarged view taken along line 8-8 in FIG. 1;

FIG. 9 is an enlarged view of the portion 9-9 in FIG. 2; and, FIG. 10 is a cross-sectional view taken along line 10-10 in FIG. 9.

In the drawings, the broken lines show portions of the tire that form no part of the claimed design.
